UNITED STATES PATENT OFFICE.

ALLEN M. SMITH, OF FORT WILLIAM MCKINLEY, PHILIPPINE ISLANDS.

DRAFT-REGULATOR FOR FURNACES.

1,245,282.

Specification of Letters Patent.

Patented Nov. 6, 1917.

Application filed November 27, 1916. Serial No. 133,645.

To all whom it may concern:

Be it known that I, ALLEN M. SMITH, a citizen of the United States, residing at Fort William McKinley, Philippine Islands, have invented certain new and useful Improvements in Draft-Regulators for Furnaces; and I do hereby declare the following to be a full, clear, and exact description of the invention, such as will enable others skilled in the art to which it appertains to make and use the same.

This invention relates to improvements in automatic damper regulators for furnaces.

One object of the present invention is to provide a device whereby opening or closing of the damper will take place, only, at a predetermined time.

Another object is to provide a device of this character wherein the operation of opening and closing the damper will continue to take place as the temperature rises and falls, after the time mechanism has been brought into play.

Another object is to provide a device of this character wherein novel means hold the parts of the damper actuating mechanism in one direction of its movement until automatically shifted by a change in temperature.

Other objects and advantages will be apparent from the following description when taken in connection with the accompanying drawing.

In the drawing:

Figure 1 is an elevation of my regulating device in connection with a furnace,

Fig. 2 is an enlarged elevation of the thermostat,

Fig. 3 is an enlarged elevation of the thermostat with the clock removed,

Fig. 4 is an enlarged vertical sectional view on the line 4—4 of Fig. 2,

Fig. 5 is an enlarged vertical sectional view on the line 5—5 of Fig. 1,

Fig. 6 is a rear elevation of the clock,

Fig. 7 is a diagrammatic view of the wiring of the device.

Referring particularly to the accompanying drawing, 10 represents a vertically disposed casing in which is arranged a vertical thermostatic bar 11. Secured to and extending through the lower end of the bar is a pin 12, the ends of which are provided with sharpened portions 12', for engagement in the hollow ends of the contact

screws 13 carried by the opposite sides of the lower end of the casing. These screws are provided with the heads 14, externally of the casing for purpose of adjustment thereof. Mounted on the front of the casing, and closing the same, is a removable plate 15, carrying a thermometer tube 16.

Carried by the lower end of the casing is a wooden or other insulated base 17, through which extends a pin 18, said pin being rigidly held for a purpose which will be later set forth. Mounted on the outer face of the base is a bracket 19, through which is formed an opening 20 for the slidable reception of a plunger 21. In the base 17 beneath the bracket, is an opening in which is secured one end of a conductor wire 22. This wire is held in place by the binding screw 23, which in turn holds an insulated washer 24 on the outer face of the base. On the plunger, inwardly of the bracket, is a transversely extending pin 35, against which bears one end of a coil spring 26. This spring encircles the plunger, and bears with its other end against the face of the base 17, the insulated washer 24 being received in this end of the spring to hold the same from lateral movement tending toward contact with the screw 23. Connecting the screws 13' and 23 is the beforementioned conductor wire 22. Connected to the pin 18, at the rear of the base 17, is another conductor wire 27, which will be more fully explained later. At two diametrically opposite points on the outer face of the base 17 are the metallic plates, each of which is formed with a keyhole slot 28, for the reception of the screws carried by the back of the clock 29.

From an inspection of the drawing, it will be seen that when the clock is placed in its proper position on the base 17, the metal casing thereof will force the plunger 21 inwardly, against the tension of the spring 26, so that the inner end of said plunger will contact with screw 23, to which the wire 22 is attached. The clock is of the ordinary alarm type, and includes the winding stem 30, for the alarm mechanism thereof.

Mounted above the furnace 31, at a suitable point, is a pair of casings or housings 32, supported by a connecting bar or beam 33. In each of these casings or housings are arranged the electromagnets 34 and 34' each set of which is provided with the armature 35, carried by one end of the centrally piv-

oted lever 36, which lever is mounted in a depending bracket 37 carried by the beam 33, between the housings. The ends of the bar extend through the housings, as clearly shown, the one projecting end being connected to the draft door 38 of the furnace by means of a chain 38, while the other end is equipped with a weight 39. Pivotally mounted within each housing, over the end 10 of the bar or lever 36, is a weighted arm 40 which is adapted to fall on the said end of the lever to prevent rebound thereof when drawn downwardly by the electromagnets. This weighted arm is, however, only heavy 15 enough to hold the lever from rebound, but on the other hand can be easily and quickly raised by the lever when the opposite end is drawn down by the other set of magnets. The sets of magnets are connected by a conductor 41, a common return wire 42 leading therefrom to a set of batteries, or other source of electricity. The batteries are represented at 43, from the other side of which extends a conductor 44, said conductor being 20 connected with the thermostatic bar 11. The connections to the electromagnets are properly led through circuit breakers or switches, each including the jaw 46, which is connected to the adjacent magnet by the 25 wire 46', and the pivoted gravity arm 47, one of said arms being connected to the contact screw 13 by the wire 45, and the other to the pin 18 by the wire 27, so that when the lever 36 rocks in either direction on its 30 pivot, it will engage with one of the arms and swing the arm out of contact with the jaw 46 and thus break the circuit from the magnets last energized. It will be readily understood that when the said lever rocks in 35 one direction it raises the draft door of the furnace, through the chain, while when it rocks in the opposite direction it permits the door to fall into closed position, by gravity.

40 If desired, I may provide the wiring with a common screw connection plug so that the ordinary electric lighting circuit may be used. This is, of course, optional and is thought to need no illustration.

45 It will be understood, from the foregoing, that when the temperature rises above a predetermined point, the thermostatic bar will bend toward the contact screw 13, so as to contact therewith. This completes a circuit 50 through the left hand set of electromagnets, of Fig. 1, and draws the adjacent end of the lever 36 down, with the result that the draft door will be permitted to fall into closed position. If, however, the temperature 55 falls below the predetermined point, nothing will take place, except that the thermostatic bar will bend into contact with the other screw 13', for the reason that

there is no connection between the clock casing and the pin 18. When, however, the alarm of the clock goes off at the predetermined time, the winding stem thereof will turn until it contacts with said pin 18, thus completing the circuit through the other set of electromagnets and causing the rocking 70 of the lever 36 in the other direction, with the result that the draft door will be lifted into open position and the fire allowed to burn up. It will be understood that when the alarm mechanism is wound up, the finger piece of the stem is left in a vertical position so that it will not touch the pin 18. 75

Attention is particularly called to the peculiar arrangement of the alarm winding stem and the contact pin 18, which automatically controls the closing of the circuit. This is particularly adapted for use at night, the alarm being set to go off at, say six o'clock, whereupon the winding stem will turn into contact with the pin 18. During 85 the night the temperature falls considerably below the normal, but it is not desirable to have the draft door opened in the middle of the night and the fire permitted to burn up and possibly result in fires or in 90 burning out. Therefore, no matter how far below the normal the temperature may fall, during the night, the draft door will not be actuated until the alarm goes off and completes the circuit through the pin 18. 95

What is claimed is:

A draft regulator for a furnace including electrically operated draft door means, and a circuit controlling device consisting of a support including an insulated base, a thermostatic bar mounted on the support, contacts carried by the support for engagement by said bar, a pair of metallic brackets mounted on the base and formed with key-hole slots, a stationary contact element carried by the base, a resiliently supported metallic pin mounted for movement toward and away from the contact element, a rigidly mounted metallic pin also carried by the base, a metallic clock having headed members engaging detachably in the keyhole slots and in metallic contact with the said brackets and with the resiliently supported pin, whereby said pin is forced into contact with the stationary element, a winding 100 alarm stem carried by the clock for engagement with the rigid pin, and a source of electricity including the said contacts and the door means in the circuit thereof. 105

In testimony whereof, I affix my signature, in the presence of two witnesses.

ALLEN M. SMITH.
